UNITED STATES. PATENT OFFICE.

JOSEPH L. WRIGHT, OF CLEVELAND, OHIO, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,298,850.

Specification of Letters Patent.

Patented Apr. 1, 1919.

Application filed May 7, 1913. Serial No. 766,096.

To all whom it may concern:

It is known that I, JOSEPH L. WRIGHT, a citizen of the United States, residing at Cleveland, in the county of Cuyahoga and State of Ohio, have invented a certain new and useful Improvement in Telephone-Exchange Systems, of which the following is a full, clear, concise, and exact description, reference being had to the accompanying drawings, forming a part of this specification.

My invention relates to telephone exchange systems, and particularly to that class known as semi-automatic. In systems of this character the lines of calling subscribers are automatically connected to an operator's position. This position is provided with a suitable sending device for controlling the action of the automatic switches for extending the calling line to the line of the called subscriber.

Instead of using automatic switches to connect the calling lines to the operators' positions, I use a combination of relays. These relays are formed into groups, there being what may be termed a set of tens and a set of units relays in each group. The tens and units relays in acting form certain combinations, such combinations connecting the calling lines to the operators' positions. The method of forming cross combinations between a set of tens and units relays is disclosed in Letters Patent 939,186, E. E. Clement, November 2d, 1909. In the present system however, this plan is enlarged upon and these tens and units relays effect connections in the following manner:

1st. By means of a set of tens and units relays the calling line is connected by primary selection to what is termed a primary trunk. Each primary trunk terminates in a first selector switch.

2d. The primary trunk is connected by a secondary selection by means of a set of tens and units relays to what is termed a secondary trunk.

3d. The secondary trunk by a third or tertiary selection by means of a set of tens and units relays is connected to an operator's position.

The operator's position in the present instance is equipped with a keyboard by which the automatic switches are controlled so as to effect connections between calling and called subscribers.

After the connection has been established, the apparatus used in the secondary and tertiary selection is automatically disconnected from the primary trunk and is in condition to be operated by other calls. 60

With this method of selection which might properly be called universal selection it is possible to connect any calling line to any operator's position. At night or during slack hours all calls can be handled from one position regardless of the size of the exchange. 65

Some of the novel features in this system in addition to the method of using and controlling sets of tens and units relays are as follows:

The sending device which controls the action of automatic switches:

The method of automatically ringing in the connector circuit: 75

Emergency switches used in conjunction with the primary, secondary and tertiary selections so as to guard or protect the apparatus used in case of faulty connections.

My invention is illustrated in the accompanying drawings, wherein: 80

Figure 1 shows a group of subscribers' line circuits and a series of tens and units primary relays for connecting the lines to primary trunks. 85

Fig. 2 shows a primary trunk with its associated first selector switch.

Fig. 3 shows a second selector switch. 90

Fig. 4 shows a connector circuit with its associated switch for selective ringing.

Fig. 5 is a duplication of Fig. 1 and represents the called subscribers' line equipments.

Fig. 6 shows a set of relays and switches for controlling the primary relays and a primary trunk. 95

Fig. 7 shows a set of relays and switches for controlling a set of secondary tens and units relays.

Fig. 8 shows a tens and units relays for connecting the primary trunk to the secondary trunk. 100

Fig. 9 shows the circuits of a secondary trunk.

Fig. 9^a is a modification of Fig. 9. 105

Fig. 10 shows the control circuits for the tertiary set of tens and units relays.

Fig. 10^a is a modification of Fig. 10.

Fig. 11 shows a tertiary set of tens and units relays for connecting the secondary 110

trunk to the tertiary trunk with which is associated an operator's key-board and sending device.

Fig. 11* is a modification of Fig. 11. 5 Fig. 12 shows a tertiary trunk for controlling the operation of the key-board and sending device.

Fig. 12* is a modification of Fig. 12.

Fig. 13 shows an operator's key-board and sending device.

Fig. 14 shows one arrangement or plan of primary, secondary and tertiary selection.

Fig. 15 shows the arrangement of the various sheets in accordance with the plan shown in Fig. 14.

Fig. 16 shows another plan of primary, secondary and tertiary selection.

Fig. 17 shows the arrangement of the various sheets in accordance with the plan shown in Fig. 16.

Referring to Fig. 1, the subscribers' stations shown at A, A¹, A², A³ and A⁴ are equipped with apparatus usual in common battery stations. Each line is provided 25 with an individual line and cut-off relay.

In the present arrangement, I have shown lines to be numbered 21, 31, 32 and 42, so as to show how various combinations of lines can become connected to primary trunks 30 through the same set of relays by having the relays themselves in acting perform certain cross combinations.

For each group of one hundred lines, where ten per cent. trunking is used, there 35 will be ten tens relays and ten units relays for each primary trunk. The tens relays are numbered from 1 to 10, while the units relays are numbered from 11 to 20.

Each one of the tens relays of a set contains the terminals of ten lines, so it therefore follows that ten relays will care for one hundred lines. For each additional primary trunk, there will be another set of tens and units relays and in case ten primary trunks are provided, the subscribers' lines will be multiplied ten times.

Corresponding contacts in the tens relays of a certain set are multiplied and connected to contacts in the units relays of the same 60 set in the following manner: The multiples of number one set of contacts of the tens relays are connected to contacts in the first units relay while the multiple contacts of the second set of contacts in the tens relays 65 are connected to the contacts in the second units relay.

When the first tens relay and the first units relay of one set is energized, it naturally follows that the line connected to the 70 first set of contacts in the first tens relay is connected to contacts in the first units relay.

The contacts in the units relays which engage contacts leading to the multiple connections in the tens relays are connected

directly to wires leading to primary trunks. These primary trunk wires are multiplied to the contacts in each units relay of its set. When the first tens and the first units relays are energized, it therefore follows that 70 the line connected to the first set of contacts in the first tens relay is connected to a primary trunk.

If the subscriber whose line is number 31 should originate a call, the action of his line 75 relay through the control circuit would energize tens relay 2 and units relay 11, thereby connecting his line to the primary trunk.

Subscriber 32 originating a call would cause tens relay 2 to become energized and 80 the units relay 12, thereby connecting his line to the primary trunk.

It is only possible for one tens and one units relay in a certain set to become energized at the same time. When a tens and 85 units relay of a set are energized, the rest of the relays of a set are prevented from operating and the control circuit is shifted to the next set of tens and units relays to place them in operative condition. 90

Referring to Fig. 6 a group of relays for controlling the action of the tens and units relays in Fig. 1 is provided to prevent interference in case of simultaneous calls from the same group of line relays. If some provision were not made then in case of such calls, more than one tens and one units relay could become energized in the same primary set. 95

Relay 382 is individual to a primary 100 trunk, while the rest of the relays shown in this figure are common to a group of one hundred lines. There will be ten relays 321 to 330, ten relays 331 to 340 and ten relays 341 to 350. Each of the relays 321 to 105 330 is individual to a group of ten line relays, while a set of relays 331 to 340 are controlled by the set of relays 321 to 330. Relay 321 controls relay 331, and relay 322 controls relay 332, etc. Each relay in the 110 set 331 to 340 is provided with eleven sets of contacts in order to enable a tens relay in the primary set to be operated, and also to allow any one of the ten units relays in the primary set to be operated. The 115 contacts of relays 321 to 330 which operate their respective relays 331 to 340 are arranged in a series relation so that only one of the relays 331 to 340 can be operated at the same time. 120

The tens starting wire belonging to a group of ten line relays is multiplied while the units wire of each line relay is individual and connected in groups to their respective control relays 331, 332, 333, etc., as the 125 case may be.

For each group of ten line relays, the tens wire will be multiplied, enabling any relay of the ten when operated to close the circuit of its control relay in the set 321 to 330. 130

The ten units starting wires from a certain group of ten line relays are connected respectively to the windings of relays in the set 341 to 350.

- 5 The controlling contacts for operating the proper units relay in the primary set, when relay 382 is operated, are in a series relation so that the action of only one relay is effective.
- 10 By the foregoing arrangement only one of the relays in the set 331 to 340, each representing a group of ten lines can become energized at one time. The energized relay connects the units wires of its group of line
- 15 relays to the windings of the unit control relays of the set 341 to 350, and as only one of these latter relays when operated is effective, it, therefore follows that only one tens and one units relay of the primary set can be operated at the same time, no matter how many line relays are energized. A distributing switch L equipped with a set of bank contacts 360 and 362 is used for picking out an idle primary trunk
- 25 such as shown in Fig. 2. 352 is the test relay associated with a switch and is energized in series with relay 382 of an idle trunk, when such a trunk is selected.

- The action of any one of the relays of the set 341 to 350 completes the circuit of relay 351. The energizing of this latter relay removes ground from the series starting wire belonging to the group of relays 321 to 330. This arrangement is made so that only a momentary action of any one of the relays of the set 331 to 340 takes place, and consequently a corresponding action to any one of the relays of the set 341 to 350. This provision is made in case of any undue delay in the falling back of relay 382, in case a primary trunk is picked out and the proper connections are not effected. In case of such undue delay and if this provision were not made, then in case of simultaneous calls, more than one tens and units relay of the primary set would become energized and cause cross combinations to be set up.

- Switch K is an emergency switch, provided with two sets of bank contacts, 358 and 359. This switch is brought into action in case relay 352 when placed in series with relay 382 should remain energized for an abnormal period, the action of the switch K will cause the switch L to take one step and also complete the circuit of relay 63 (Fig. 1). The action of this relay will unlock any one of the tens or units relays of the primary set as their locking circuit passes through its back contacts.

- Referring to Fig. 2, a primary trunk is shown terminating in a first selector switch D. Relay 111 and retardation coil 112 are connected respectively to the tip and sleeve sides of the trunk. The relay 111 has one

terminal connected to ground while the retardation coil 112 has one terminal connected to the free side of the battery. The relay and the coil supply talking current to the calling subscriber.

70 Relay 110 is placed in series with the cut-off relay of the calling line after the tens and units relays of the primary set are operated. Relay 110 corresponds to the line relay inasmuch as it selects the proper tens 75 and units relays of the secondary trunk so as to form the combination of the calling primary trunk with which it is associated. Relay 114 is operated after the secondary and tertiary selections have been effected and 80 the primary trunk connected to an idle key-set. The action of relay 114 at this time closes the circuit of the relay 113, which in turn opens the starting wires leading to the tens and units relay of the secondary set. 85 Relay 113 after being operated, remains locked to ground through the back contact of relay 115. This latter relay is not operated until after the switch D rotates and the calling subscriber hangs up his receiver, 90 thereby deenergizing the tip relay 111. The operation of the relay 115 closes the circuit of the release magnet 121, serving to restore the switch D to its normal position. 95 Relay 119 is the test relay of the first selector switch D and is energized by a test impulse from the sending device and remains energized while the test wiper 142 is passing over busy or grounded contacts. The operation of relay 119 completes the 100 circuit of relay 117, and in operating severs the trunk conductors so as to prevent interference while the wipers of the switch D are passing over busy contacts.

105 Relay 109 is a slow acting relay energized by the action of the relay 111. The action of the former relay serves to prevent disconnection in case the calling subscriber should accidentally move his receiver hook. While the relay 109 is energized, the release circuit of the switch D is disabled. This release circuit can only become effective when relay 109 is in its normal position and relay 117 and 115 are 110 energized. This condition prevails after 115 the switch D has rotated and stepped vertically. After the switch steps in a vertical direction and the wipers 142 and 143 engage test contacts leading to the second selector switch, then these two wipers become 120 short circuited and completes the circuit of relay 117 to ground through the back contact of the relay 116.

125 It will be noted that the two wipers 142 and 143 are separated; wiper 142 serving as a test wiper, while the other serves to control the release. The release relay 115 when energized opens the locking circuit of the tens and units relays of the primary set, thereby freeing the calling line 1

from the primary trunk. After a subscriber's line once becomes connected to a primary trunk, it can only be freed therefrom by the action of the first selector switch engaging test contacts, thereby short circuiting the wipers 142 and 143.

One row of contacts in the bank can be so arranged to prevent the release of the switch or the calling subscriber. Instead of connecting the two contacts together which the wipers 142 and 143 engage, they can be independent of one another and so prevent the release circuit from being closed.

Relay 115 is a vibrating relay and used in conjunction with the vertical magnet 118 causing the switch D to automatically step after the test impulse has been delivered. This relay also connects ground to the locking contact of the test relay 119, so that when this latter relay is energized, it cannot become deenergized until the test wiper 142 engages an idle contact and relay 116 is energized. Relay 116 becomes energized however just as soon as the vertical magnet 118 completes its stroke, and at this time the wiper 142 engages a test contact.

122 is the repeating relay and responds to impulses from the sending device. The winding of this relay is connected to battery in series with the resistance coil 162. The operation of the rotary magnet 120 connects ground between the winding of the relay and the resistance coil so that when the relay 122 operates and closes the circuit of the magnet 120, then the magnet itself when completing its stroke will connect ground between the coil and the relay winding, thereby shunting the latter. The impulses from the sending device are delivered from the grounded side of the battery so that in case the impulses are a trifle long or irregular, the magnet 120 will shunt the relay 122 regardless.

Ground being placed between the winding of the relay and the coil at each stroke of the magnet also serves to dissipate any static charge which may have accumulated on the impulse conductors. The tip and sleeve conductors of the primary trunk are separated by the condensers 148 and 149 in the usual manner.

Referring to Fig. 3, the second selector switch is shown at E. 162 is the rotary repeating relay which responds to impulses from the sending device, causing the switch E to step in a rotary direction. 167 is the test relay and responds to the test impulse from the sending device and when operated closes the circuit of the vertical magnet 165, causing the switch E to step vertically until an idle connector switch is found. Relay 164 is energized by the action of the relay 167 and in operating, severs the trunk connectors so as to prevent interference. 161 is the vibrating relay, serving to open and

close the circuit of the vertical magnet 165 and also to insure a full stroke of the vertical magnet. This relay maintains the circuit of the relay 167 closed until after its own circuit is closed, which happens when the vertical magnet 165 completes its stroke.

Relay 163 serves to control the release circuit and also to render the test contacts in the first selector switch busy, while the switch E is restoring. This relay is operated by the first movement of the relay 162 and in operating, locks itself to ground over the test wire 152. The circuit of the release magnet 168 is closed when relay 167 is de-energized and relay 164 energized. The foregoing combination takes place when ground is removed from the test wire 152, relay 163 deenergized and the switch E in an off-normal condition. When the switch is in such a condition, the rotary cam springs 157 are closed and ground connected to the winding of relay 164. This relay will remain energized until the switch reaches its normal position. At the first vertical step of the switch E the cam springs 158 are operated, thereby disconnecting relays 167 and 162 respectively from the trunk conductors.

Referring now to Fig. 4, the connector switch G, and its associated selective ringing switch F is shown. Relays 270 and 272 are the repeating relays and respond to impulses from the sending device. One terminal of each relay is connected to battery in series with the resistance or regulating coil 271. 275 is a locking or control relay operated by the action of relay 272. Relay 275 has its circuit opened at the first action of the relay 270. Relay 276 and the retardation coil 280 connected respectively to the grounded and free side of the battery, furnishes talking current to the called subscriber. Relay 277 is placed in series with the cut-off relay of the called line when the connection is complete. The action of relay 277 completes the circuit of the relay 282. The action of this latter relay connects generator current of the frequency selected by the switch F, to the called line. The generator current of the frequency selected passes through a suitable associated commutator. Relay 283 is operated intermittently and is energized during the non-ringing interval and connects the tip relay 276 to either the tip or sleeve side of the line as the case may be. The shifting of the tip relay and the selecting of the proper frequency of the ringing current is determined by the action of the switch F.

The switch F is provided with three portions consisting of a wiper and associated contacts shown at H, I and J. The contacts and wiper of the portion J cut on the generators 256, 257, 258 or 250 to either the tip or sleeve contacts of the ringing relay 282. The contacts and wiper of the portion

I serve to restore the switch F to its normal position at the proper time. The contacts and wiper of the portion H serve to connect the coil 300 to either the tip or sleeve contacts of the relay 282. When the portion J connects generator current to the tip contact, the portion H connects coil 300 to the sleeve contact and when the portion J connects generator to the sleeve contact, the portion H connects relay 276 to the tip contact. With this arrangement, it is possible to ring subscribers' bells which are connected to either the tip or sleeve side of the line to ground or if they are bridged directly across the tip and sleeve conductors. The resistance coil 300 is connected to the wire 209 and at each operation of the relay 283 this coil is placed in multiple with the winding of the relay 276. The resistance of this coil is arranged so that when the called party answers, the relay 276 will operate.

The portion H of the switch F also serves to release the connector switch G after the called subscriber hangs up his receiver or when the calling subscriber hangs up, in case the called subscriber does not answer.

When the switch F is in its normal position, the wiper of the portion H rests on contact 234, the wiper of I on contact 236, while the wiper of J rests on contact 238. A suitable ring-back tone test 213 is connected back to the calling line at each operation of the relay 283, thus notifying the calling party that the called subscriber is being rung. This tone test is in series with a suitable condenser 212 and retardation coil 210.

When the called subscriber answers during a non-ringing interval, which will be when relay 283 is energized, then relay 276 becomes energized and in acting unlocks relay 279, which upon falling back opens the circuit of relay 282, thereby preventing any further action of the ringing current. Relay 282 falling back disconnects relay 283.

274 is the test relay and is operated in case the called for line is busy. In such an event the action of this relay closes the circuit of the release magnet of the switch G, thereby restoring it to its normal position. The action of this relay also connects a suitable busy tone test to the calling subscriber, notifying him that the called for line is busy.

Referring now to Fig. 5, the circuits shown are the same as those in Fig. 1 and need not be described.

Referring now to Fig. 7, a set of relays and switches for controlling the set of tens and units relays of the secondary trunk are shown. The circuits shown herein are about the same as those in Fig. 6 and will be described in detail when tracing through a connection.

Referring to Fig. 8 the tens and units relays of the secondary trunk are shown to correspond and operate in the same manner

as the tens and units relays of the primary trunk shown in Fig. 1. There are 10 tens relays and 10 units relays for each secondary trunk. Only one tens and one units relay can become energized at the same instant, 70 due to the control circuit shown in Fig. 7.

Referring now to Fig. 9, a secondary trunk is shown. Relay 550 is placed in series with relay 114, (Fig. 2), and relay 650, (Fig. 12), when the primary trunk finally 75 becomes connected to an idle key-set.

Relay 552 is connected to the locking contacts of the tens and units relays shown in Fig. 8. The action of this relay closes the circuit of the relay 554 through the contacts 80 of relay 551. Relay 552 connects ground to the tens and units starting wires of the controlling relays, (Fig. 10), through the contacts of relay 553. Relay 551 is slow acting and is operated when relay 550 becomes energized and relay 550 serves to close the circuit of the relay 553, thereby removing ground from the tens and units starting wires.

The action of relay 554 connects relay 555 90 directly to the tip side of the trunk. This latter relay is operated by the first impulse sent over tip side of the trunk and in operating unlocks the relay 554, and as soon as this latter relay falls back, it in turn disconnects 95 relay 555 from the tip side of the trunk. Relay 552 through which the tens and units relays of Fig. 8 have their circuits locked has its own circuit jointly controlled through the contacts of relays 550, 551 and 554. 100 This circuit is closed normally through the back contact of relay 551 and through the front contacts of relays 554, 553 and 550 when these last mentioned relays are operated. After the first impulse has been transmitted over the tip side of the trunk and relay 554 unlocked, then the circuits of the tens and units relays, (Fig. 8), and the circuit of the relay 552 are maintained or controlled by the action of the relays 550 and 105 551. After all of the impulses have been transmitted and the circuit of the relay 550 broken, then this relay falls back, opens the locking circuit of the tens and units relay, thereby freeing the secondary trunk from 115 the primary trunk. Fig. 10 shows a group of relays for controlling the action of the tens and units relays of the tertiary trunk. The action of this group of controlling relays prevents more than one tens or units 120 relay of the set shown in Fig. 11, becoming energized at the same time, in case of simultaneous calls.

Relay 599 is individual to a tertiary trunk or key-set while the rest of the relays in this figure are common to a group of one hundred trunks. There will be ten relays, 451, 452, 453, etc., ten relays 561, 562, 563, etc., and ten relays 571, 572, 573, etc., common to each group of 100 trunks. Relay 451 is 130

common to a group of ten trunks, while relays 452 and 453 are each common to a group of ten trunks. Each of the relays 451, 452, 453, etc., controls an associated 5 relay 561, 562, 563, etc. The last mentioned relays are equipped with eleven sets of contacts in order to enable a particular tens relay for the set to be operated and also to allow any one of the units relays 10 to become operated. It will be noted that the contacts of the relays 451, 452, 453, etc., which operate their associated relays 561, 562, 563, etc., respectively are arranged in a series relation, so that only one of the relays 15 561, 562, or 563 can be operated at the same instant.

The tens wire belonging to a group of ten trunk relays is multiplied while the units wire of each relay is individual and they are 20 connected to ground in their respective control relays 561, 562 or 563 as the case may be. In each group of ten trunks, the tens wires will be multiplied, enabling any relay 25 of the ten, when actuated to close the circuit of its control relay, such as 451. The ten units wires from this group of the ten trunk relays, lead to normally open contacts of a control relay such as 561. Opposite contacts of the relay 561 are connected respectively to relays 571, 572, 573, etc. The contacts of the last mentioned relays are in a series relation so that no matter how many relays are held up or energized in this group, only the action of one becomes effective. By this arrangement of the control relays 561, 562, 563, etc., each representing a group of ten trunks not more than 30 one tens and one units relay can become energized at the same time.

40 The relay energized connects the units wires of its group of trunk relays to the group of unit control relays, 571, 572, 573, etc., and as only one of these relays when operated is effective, it therefore follows 45 that only one tens and one units relay of the group can be operated at the same time, no matter how many trunk relays are energized.

Referring to Figs. 12 and 13, the tertiary 50 trunk or key-set and the operator's sending device and key-board are shown. Relay 650 is placed in series with relay 550 (Fig. 9), and relay 114, (Fig. 2) when the primary trunk becomes connected to the key-set. 55 The action of the relay 650 causes the lamps 700 and 701 to light, notifying the operator of that call. The action of this relay also closes the circuit of the relay 651, which remains energized until the call has been completed. Relay 649 is arranged so as to give 60 a slight time element in shifting the starting circuits on to the next key-set or tertiary trunk. The relay 652 is the answering relay, energized when the operator presses 65 the "answer" button and connects her tele-

phone set, across the tip and sleeve conductors. 654 is the starting relay and serves to set in action the operator's controlling device. 655 is the trunk starting relay and when operated, controls or reduces the groups of impulses to be transmitted to the automatic switches. 70

The controlling device consists of two distributing switches of a rotary type. One of these switches is equipped with three 75 banks of contacts, while the other is equipped with one. The last mentioned switch X^1 has no resting or normal position, but can be left at any point with its wipers resting on any contact. The action of the 80 wiper of this switch in sweeping over its contacts simply connects ground to the starting contact, then to the ten individual contacts of the keys on the key-board in order, starting from one to ten. After 85 ground has been connected to these contacts, then the shifting contact is reached, after which the test contact is engaged. This switch will continue to rotate until the distributing switch X^2 restores to its normal 90 position after performing its functions.

At the first two rotations of the switch X^1 , the switch X^2 takes four steps. These steps are taken in the following order: When ground is connected by the wiper to 95 the starting contact, the circuit of the stepping magnet 709 of the switch X^2 is closed through the first contact of the bank 691. The action of the stepping magnet causes the wipers of the switch X^2 to leave the first 100 set of contacts. Relay 706 is provided with a high resistance winding and is placed in series with the repeating relay of the first selector switch over the tip side of the trunk to the bank 690. The stepping magnet 709, 105 after the switch X^2 takes its first step, is connected to a wire common to the first strip of buttons on the key-board. As soon as the wiper of the switch X^1 reaches the contact leading to the depressed button in 110 this first step, then the circuit of the stepping magnet 709 will again be completed and cause the wipers of the switch X^2 to take another step, thereby disconnecting relay 706 from the repeating relay of the first 115 selector. The action of the stepping magnet 709 in causing the switch X^2 to take another step, causes the magnet itself to become connected to the shifting contact in the switch X^1 . This shifting contact is connected to a contact in the bank 691 by wire 120 711. When this contact is reached by the wiper of the switch X^1 , then the circuit of the stepping magnet 709 is again completed and the wipers of the switch X^2 will engage 125 the next set of contacts. At this step of the switch X^2 , the relay 706 is placed in series with the test relay of the first selector switch over the sleeve side of the trunk through the bank 690. 130

After the wiper of the switch X^1 reaches the shifting contact, causing the switch X^2 to take another step, then the magnet 709 is connected through the bank 691 to the test contact in the switch X^1 . This test contact is connected to a contact in the bank 691 of the switch X^2 by wire 712. As soon as the wiper of the switch X^1 reaches the test contact, then the circuit of the stepping magnet 709 is again closed causing the switch X^2 to take another step.

From the foregoing it will be noted that the switch X^2 takes four steps at the first complete rotation of the switch X^1 .

The switch X^1 will continue to rotate until all of the impulses have been transmitted to the first selector, second selector and connector switches after which the switch X^2 returns to its normal position and the switch X^1 comes to rest. During the stepping of the switch X^2 the circuit of the relay 706 is constantly interrupted. When the starting button is first pressed, the circuit of this relay is completed to battery through the resistance coil 735 through the first contact in the bank 690 of the switch X^2 . As soon as 706 becomes energized it closes the circuit of the stepping magnet 707 of the switch X^1 . As soon as the magnet completes its stroke, ground is connected between the winding of the relay 706 and the coil 735, thereby shunting the former. As soon as the relay 706 is shunted, it falls back and opens the circuit of the stepping magnet 707 thereby removing the shunt and it at once becomes energized again. This action will continue until the energizing circuit for relay 706 is finally broken. After the switch X^2 takes its first step, the circuit for relay 706 is maintained in series with the repeating relay of the first selector switch. After the second step of the switch X^2 , the circuit for the relay 706 is again maintained to the resistance coil 735. At the third step of the switch X^2 , the circuit for relay 706 is closed through the test relay of the first selector switch. At the fourth step of the switch X^2 , the circuit for the relay 706 is maintained through the resistance coil 735. The relay 706, as stated, is of a high resistance, the resistance being such that the repeating relays of the first selector, second selector and connector switches will not pull up in series with it. The relay 706 however will pull up in series with any of the repeating relays and in doing so, connects ground directly to the stepping magnet 707. As soon as the stepping magnet completes its stroke, it closes its associated contact springs and places ground directly to the winding of the relay 706, thereby shunting it. This ground besides shunting the relay 706 also causes the repeating relay of the selector or connector switches as the case may be to become energized. These repeat-

ing relays are in series with a regulating or resistance coil and when energized, close the circuits of their respective stepping magnets. As soon as the stepping magnet completes its stroke, ground is connected directly between the winding of the repeating relay and the resistance coil with which it is in series. While this ground is placed between the relay and the resistance coil, the relay 706 cannot become energized even though the magnet 707 falls back and removes ground from the winding of the relay itself. The relay 706 is therefore controlled not only by the action of the magnet 707 but also by the magnet or magnets of the selector and connector switches.

The foregoing method of regulating or controlling the stepping of the magnets of the selector or connector switches and the magnet of the switch X^1 causes the selector and connector switches to step in unison with the magnet of the switch X^1 .

The number of impulses in any one group is determined or regulated by the number of steps the switch X^1 takes in finding the depressed key in the row on the key-board. The key-board consists, in the present instance, of five rows or strips of buttons of the usual locking or indicating type, there being ten buttons to each strip. When any one button of a certain row is depressed, it will release the button formerly depressed. The buttons 703, 704, 705, are of the non-locking type and simply close their associated contact springs while the button is being depressed.

We will now trace the connection from the calling to the called subscriber using various figures arranged in accordance with Fig. 15, after which modifications as shown in the arrangement in Fig. 17 will be described.

We will assume that subscriber at station A, whose line is No. 21 is the calling party. The removal of the receiver closes the circuit of the line relay 42 as one terminal of this relay is connected to ground, the other terminal being connected to one side of the line through the contacts of the relay 41. A resistance coil, one terminal of which is connected to the free side of the battery and the other terminal connected to the opposite side of the line through the contacts of the relay 41, causes a complete circuit to exist after the receiver is removed. The operation of the relay 42 closes the circuit of the relay 321 as follows: ground, contacts of relay 42, 71, 321, to battery B. The operation of the relay 321 completes the circuit of the relay 331 by the following path: ground, contacts of relay 351, 305, contacts of relay 321, 308, 331 to battery B. As the relay 331 is energized, the circuit of the relay 341 is closed as follows: ground, contacts of relay 42, 74, contacts of relay 331, 370, 341, to battery B.

The operation of relays 331 and 341 connects ground to the tens and units contacts in relay 382. The circuit of the relay 382 is closed as follows: battery B, winding of relay 352, 312, contacts of relay 321, 374, contacts of the portion 362, of the switch L, 365, 382, 83, to ground through the contacts of the relay 110 (Fig. 2).

Ground being connected to the tens and units wires through the contacts of the relay 382, which is now energized, completes the circuit of the tens relay 1, and the units relay 11, Fig. 1.

The operation of the tens and units relays for the primary set connects calling line No. 21 directly to the primary trunk, Fig. 2. As soon as this connection is made, relay 110 is placed in series with relay 41 as follows: battery B, 110, 58, contacts of relay 11, 55, contacts of relay 1, 52, 41, to ground. The operation of the relay 110 removes ground from the winding of the relay 382, thereby causing it and relay 352, with which it is in series, to fall back.

The energizing of the relay 41 disconnects the line relay 42 and the resistance coil from the calling line. Relay 42 falling back removes ground from the winding of the relay 321 which falling back in turn opens the circuit of relay 331.

When relay 341 became energized, it closed the circuit of the relay 351 and the operation of this latter relay removes ground from the contact of the relay 321, thereby releasing relay 331. Relay 331 falling back removes ground from winding of the relay 341. The falling back of the relays 331 and 341 removes ground from the tens and units wires connected to contacts of relay 382. It will thus be seen that ground is only connected momentarily to the tens and units wires through the contacts of the relay 382. This momentary ground however is maintained for sufficient time for the tens and units relays of the primary set to become energized. Relay 351 is slow acting and prevents the series starting circuit being closed again until relay 321 has dropped back. As soon as the tens and units relays are once energized their circuit is maintained to ground through the contacts of the relay 115 (Fig. 2).

After the line of the calling party is connected to the primary trunk battery supply is furnished for talking purposes through the retardation coil 112 and relay 111. Relay 111 at once becomes energized and completes the circuit of the slow relay 109 so as to maintain the release circuit open until the proper time.

The operation of the relay 110 connects ground to the tens and units starting wires through the contacts of the relay 118, thereby closing the circuit of the relay 421, Fig. 7. The operation of this latter relay com-

pletes the circuit of the relay 431 as follows: ground, contacts of relay 471, contacts of relay 421, 408, 431 to battery B. The operation of the relay 431 connects ground to the tens contact in relay 419 over wire 469 and also connects ground to the units contact in relay 419, over wire 468. As soon as relay 431 is energized, the circuit of the relay 441 is closed to ground through the contacts of relays 110, 113 and 431.

The operation of the relay 421 completes the circuit of the relay 472 which in turn completes the circuit of the stepping magnet 473 of the switch N as follows: ground, contacts of relay 472, 404, contacts of relay 470, 417, contacts of the vibrating relay 474, 473, battery B. The switch N will continue to step until an idle secondary trunk is found whereupon the circuit of the test relay 470 is completed as follows: battery B, 470, 412, contacts of relay 421, 484, portion 482 of the switch N, 465, 419, 501, contacts of relay 553, (Fig. 9), 556 to ground through the contacts of relay 551. As soon as this circuit is completed, relay 470 becomes energized and opens the circuit of the stepping magnet 473.

The energizing of the relay 419 closes the tens and units contacts thereby completing the circuits of tens and units relays 521 and 531 respectively. The circuit of the former is closed from ground through the contacts of the relay 431, while the circuit of the latter is completed from ground through the contacts of the relay 441. This ground is only maintained momentarily for as soon as relay 441 becomes energized, the circuit of the relay 471 is completed thereby removing ground from the contact of the relay 421 which opens the circuit of the relay 431.

Relay 431 in falling back opens the circuit of the relay 441, which in turn opens the circuit of relay 471. Relay 471 is slow acting and prevents the series starting circuit being closed again until relay 421 has fallen back. After this momentary ground has passed, the circuits of the relays 521 and 531 are maintained to ground through the contact of the relay 551, Fig. 9, in series with the winding of the relay 552. Relay 552 at once becomes energized and completes the circuit of the relay 554 as follows: ground, contacts of relay 552, 542, contacts of relay 551, 541, 554, to battery B. The operation of relay 554 connects one terminal of the relay 555 directly to the tip conductor 513.

The operation of the relay 552 also connects ground to the tens and units starting or controlling wires through the back contacts of the relay 553, thereby closing the circuit of relay 451, Fig. 10. The operation of this latter relay completes the circuit of the relay 561 and this relay in turn connects ground to relay 571 as follows: ground, contacts of relay 552, contacts of relay 553, 547, contacts of relay 561, 584, 571 to battery

B. The operation of the relay 561 connects ground to the tens relay, Fig. 11, through the contacts of the relay 599. The operation of relay 571 connects ground to the units 5 relay, Fig. 11.

The contacts controlling relays 561, 562, 563, etc., are in a series relation so that the operation of only one of the relays 451, 452 or 453 can become effective. The contacts 10 of the relays 571, 572, 573, are also in a series relation so that only one units relay of the set, Fig. 11, can become energized at the same time. The circuit of the relay 599 of an idle tertiary trunk is completed as follows: ground, contacts of relay 451, 598, 15 contacts of relay 651, Fig. 12, 669, contacts of relay 653, 670, 621, 599, to battery B. The operation of relay 599 allows relays 601 and 611, Fig. 11, to become energized by 20 means of ground connected to the contacts of the relays 561, and 571. After relays 601 and 611 are operated, their circuit is maintained through their locking contacts to ground through the contacts of relay 653, 25 Fig. 12.

The operation of the relays 601 and 611 places relays 650, Fig. 12, 550, Fig. 9, relay 114, Fig. 2, in series, as follows: ground, contact of relay 653, 656, contacts of relay 30 654, 661, contacts of relay 652, 662, winding of 650, 634, contacts of relay 611, 624, contacts of relay 601, 545, winding of 550, 518, contacts of relay 531, 508, contacts of relay 521, 108, contacts of relay 115, 109, winding 35 of 114 to battery B.

The operation of relay 114 completes the circuit of the relay 113 which in operating removes ground from the tens and units starting wires and relay 421, Fig. 7, falls 40 back. The circuit of relay 113 is maintained closed to ground, through the back contact of the relay 115.

The operation of the relay 550, Fig. 9, completes the circuit of relay 551 and also 45 the circuit of the relay 553. The operation of the latter relay removes ground from the tens and units starting wires leading to Fig. 10. The operation of the relay 551 removes ground from the winding of relay 50 552, but ground is also connected to the winding of this relay through the front contacts of the relay 554, which became energized at the operation of the relay 552. The operation of the relay 551 also removes 55 ground from the winding of the relay 554 but the circuit of this relay is maintained to ground through the back contact of the relay 555. The operation of relay 553 removes ground from the relay 451, Fig. 10, 60 which on falling back, opens the circuit of the relay 561. The operation of the relay 650, Fig. 12, closes the circuit of the relay 651, and also causes the two lamps 700 and 701 to light. The operation of the relay 651 65 disconnects the starting wire 598 from the

winding of the relay 649 and of the relay 599, Fig. 10, thereby rendering the selected trunk busy against other incoming calls. Relay 649 was energized in multiple with relay 599 and while energized opens the 70 starting wire 672, leading to the next trunk. However after the operation of 651, then relay 649 falls back and the starting circuit is then completed, or continued to the starting wire 672. The operation of the relay 75 651 also places the relay 652 under control of the answering button 705, Fig. 13. The circuit of the relay 651 after once completed, is maintained to ground through the back contact of the relay 653. 80

It will now be seen that the calling subscriber is connected directly to an idle keyboard through the primary set of relays, the secondary set of relays and the tertiary set of relays and the common control circuits 85 are free to be used for other incoming calls.

After the two lamps 700 and 701 are lighted, the operator presses the answering button 705, thereby closing the circuit of the relay 652. The operation of this relay 90 connects the operator's telephone-set across the tip and sleeve conductors 633 and 635. The operation of this latter relay also disconnects relay 650 thereby causing it and relays 550 and 114 which are in series to fall 95 back. Relay 650 falling back extinguishes the lamps 700 and 701. Relay 550 falling back produces no other result than that of unlocking relay 551. Relay 114 however falling back closes the tip and sleeve conductors of the primary trunk, allowing the operator to converse with the calling subscriber. After receiving the number desired, the operator sets up the number on her keyboard by pressing a button in each 100 one of the rows, 694, 695, 696, 697 and 698. After these buttons are pressed which represent the number of the called party, then the starting button 704 is pressed, closing the circuit of the relay 654 by the following 110 path: ground, contacts of button 704, 678, 654, 634, contacts of relay 611, 624, contacts of relay 601, 545, 550, 518, contacts of relay 531, 508, contacts of relay 521, 108, contacts of relay 115, 109, 114 to battery B. The 115 operation of the relay 654 disconnects relay 652, thereby removing the operator's telephone set from the tip and sleeve conductors. The operation of the relay 654 closes the circuit of the guard lamp 701. This 120 lamp remains lighted while the connection is being built up. Relay 654 also completes the circuit of the relay 706 by the following path: ground, 706, 664, contacts of relay 654, 665, first contact of the portion 690 of the 125 switch X² and coil 735, to battery B. The operation of the relay 706 closes the circuit of the stepping magnet 707 of the switch X¹, causing it to rotate in the direction indicated by the arrow. When the first or 130

130

starting contact is reached, the circuit of the stepping magnet 709 of the switch X^2 is closed by the following path: ground, contacts of relay 706, 719, 693, starting contact 5 720, first contact of the portion 691 of the switch X^2 , 668, contacts of relay 708, 709, to battery B. The closing of this circuit causes the wipers of the switch X^2 to leave the first set of contacts and to engage a 10 second set of contacts. After this switch X^2 takes the first step relay 706 is disconnected from the coil 735 and placed in series with relay 122, Fig. 2, by the following path: ground, 706, 664, contacts of relay 654, 665, 15 690, 633, contacts of relay 611, 623, contacts of relay 601, 513, contacts of relay 531, 503, contacts of relay 521, 103, cam springs 127, 126, 119, to battery B. The operation of relay 706 closes the circuit of the magnet 707 causing the switch X^1 80 to take one step whereupon the shifting contact is reached. While this step however is being taken, the circuit of the relay 119 is closed and maintained to ground from its locking contact through the back contact 85 of relay 116. The operation of the relay 119 closes the circuit of relay 117 by the following path: ground, contacts of relay 119, 123, contacts of relay 109, 131, 117, to battery B. The operation of relay 117 90 severs the tip and sleeve conductors so as to prevent interference while the wipers of the switch D are passing over busy contacts. The operation of relay 119 also completes the circuit of the vertical magnet 118 95 through the back contacts of relay 116. As soon as the magnet 118 completes its stroke, the circuit of relay 116 is closed and the magnet circuit therefore opened and ground removed from the locking contact of relay 100 119. If the test wiper 142 should now engage an idle contact or one free from ground, then relay 119 would at once fall back and prevent any further action of the switch D. If however the first contact engaged is 105 grounded, then the circuit of relay 119 would be maintained and the switch D continue to step until an idle contact is reached. When such a contact is reached, relay 119 in falling back releases relay 117, thereby 110 closing the tip and sleeve conductors so as to allow the second selector and connector switches to be operated from the sending device.

At the first vertical step of the switch D, 115 the cam springs 127 are opened and relays 122 and 119 disconnected from the tip and sleeve conductors.

After the wiper of switch X^1 reaches the shifting contact, the magnet 709 has its circuit closed by the following path: ground, contacts of relay 706, 719, 693, shifting contact 742, 691, 668, contacts of relay 708, 709, to battery B. The closing of this circuit now causes the switch X^2 to take another step thereby placing relay 706 in series with resistance coil 735. The switch X^1 125 will continue to rotate and when the starting contact is again reached the circuit of the magnet 709 will be closed causing the 130

5 starting contact is reached, the circuit of the stepping magnet 709 of the switch X^2 is closed by the following path: ground, contacts of relay 706, 719, 693, starting contact 5 720, first contact of the portion 691 of the switch X^2 , 668, contacts of relay 708, 709, to battery B. The closing of this circuit causes the wipers of the switch X^2 to leave the first set of contacts and to engage a 10 second set of contacts. After this switch X^2 takes the first step relay 706 is disconnected from the coil 735 and placed in series with relay 122, Fig. 2, by the following path: ground, 706, 664, contacts of relay 654, 665, 15 690, 633, contacts of relay 611, 623, contacts of relay 601, 513, contacts of relay 531, 503, contacts of relay 521, 103, cam springs 127, 126, 119, to battery B. The operation of relay 706 closes the circuit of the magnet 707 causing the switch X^1 80 to take one step whereupon the shifting contact is reached. While this step however is being taken, the circuit of the relay 119 is closed and maintained to ground from its locking contact through the back contact 85 of relay 116. The operation of the relay 119 closes the circuit of relay 117 by the following path: ground, contacts of relay 119, 123, contacts of relay 109, 131, 117, to battery B. The operation of relay 117 90 severs the tip and sleeve conductors so as to prevent interference while the wipers of the switch D are passing over busy contacts. The operation of relay 119 also completes the circuit of the vertical magnet 118 95 through the back contacts of relay 116. As soon as the magnet 118 completes its stroke, the circuit of relay 116 is closed and the magnet circuit therefore opened and ground removed from the locking contact of relay 100 119. If the test wiper 142 should now engage an idle contact or one free from ground, then relay 119 would at once fall back and prevent any further action of the switch D. If however the first contact engaged is 105 grounded, then the circuit of relay 119 would be maintained and the switch D continue to step until an idle contact is reached. When such a contact is reached, relay 119 in falling back releases relay 117, thereby 110 closing the tip and sleeve conductors so as to allow the second selector and connector switches to be operated from the sending device.

At the first vertical step of the switch D, 115 the cam springs 127 are opened and relays 122 and 119 disconnected from the tip and sleeve conductors.

After the wiper of switch X^1 reaches the shifting contact, the magnet 709 has its circuit closed by the following path: ground, contacts of relay 706, 719, 693, shifting contact 742, 691, 668, contacts of relay 708, 709, to battery B. The closing of this circuit now causes the switch X^2 to take another step thereby placing relay 706 in series with resistance coil 735. The switch X^1 125 will continue to rotate and when the starting contact is again reached the circuit of the magnet 709 will be closed causing the 130

5 starting contact is reached, the circuit of the stepping magnet 709 of the switch X^2 is closed by the following path: ground, contacts of relay 706, 719, 693, starting contact 5 720, first contact of the portion 691 of the switch X^2 , 668, contacts of relay 708, 709, to battery B. The closing of this circuit causes the wipers of the switch X^2 to leave the first set of contacts and to engage a 10 second set of contacts. After this switch X^2 takes the first step relay 706 is disconnected from the coil 735 and placed in series with relay 122, Fig. 2, by the following path: ground, 706, 664, contacts of relay 654, 665, 15 690, 633, contacts of relay 611, 623, contacts of relay 601, 513, contacts of relay 531, 503, contacts of relay 521, 103, cam springs 127, 126, 119, to battery B. The operation of relay 706 closes the circuit of the magnet 707 causing the switch X^1 80 to take one step whereupon the shifting contact is reached. While this step however is being taken, the circuit of the relay 119 is closed and maintained to ground from its locking contact through the back contact 85 of relay 116. The operation of the relay 119 closes the circuit of relay 117 by the following path: ground, contacts of relay 119, 123, contacts of relay 109, 131, 117, to battery B. The operation of relay 117 90 severs the tip and sleeve conductors so as to prevent interference while the wipers of the switch D are passing over busy contacts. The operation of relay 119 also completes the circuit of the vertical magnet 118 95 through the back contacts of relay 116. As soon as the magnet 118 completes its stroke, the circuit of relay 116 is closed and the magnet circuit therefore opened and ground removed from the locking contact of relay 100 119. If the test wiper 142 should now engage an idle contact or one free from ground, then relay 119 would at once fall back and prevent any further action of the switch D. If however the first contact engaged is 105 grounded, then the circuit of relay 119 would be maintained and the switch D continue to step until an idle contact is reached. When such a contact is reached, relay 119 in falling back releases relay 117, thereby 110 closing the tip and sleeve conductors so as to allow the second selector and connector switches to be operated from the sending device.

At the first vertical step of the switch D, 115 the cam springs 127 are opened and relays 122 and 119 disconnected from the tip and sleeve conductors.

After the wiper of switch X^1 reaches the shifting contact, the magnet 709 has its circuit closed by the following path: ground, contacts of relay 706, 719, 693, shifting contact 742, 691, 668, contacts of relay 708, 709, to battery B. The closing of this circuit now causes the switch X^2 to take another step thereby placing relay 706 in series with resistance coil 735. The switch X^1 125 will continue to rotate and when the starting contact is again reached the circuit of the magnet 709 will be closed causing the 130

- switch X^2 to take another step, thereby placing relay 706 in series with relay 162, Fig. 3, over the tip conductor. The switch X^1 and the switch E, Fig. 3, will step in unison, 5 and when the wiper of the switch X^1 engages a contact leading to the depressed button in the row 695, the circuit of the magnet 709 is closed thereby disconnecting relay 706 from relay 162. Relay 162 having 10 its circuit broken, will cause the switch E to come to rest with its wipers in line with a set of contacts corresponding to the button depressed in the row 695. The relay 706 however will have its circuit completed 15 through the coil 735 and thereby cause the switch X^1 to continue rotating. When the test contact is reached, the magnet 709 will have its circuit completed causing the switch X^2 to take another step and place the relay 20 706 in series with the test relay 167, Fig. 3, over the sleeve conductor. The switch X^1 after taking another step engages the shifting contact, thereby closing the circuit of the magnet 709 causing the switch X^2 to 25 take another step, thereby disconnecting relay 706 from relay 167. The circuit of the relay 706 will however be maintained through the coil 735. The circuit for relay 167 will be maintained from its locking contact to ground through the back contact of the relay 161. The action of relay 167 closes 30 the circuit of the relay 164 which severs the tip and sleeve conductors so as to prevent interference while the wipers of the switch 35 E are passing over busy contacts. The action of relay 167 also closes the circuit of the vertical magnet 165 from the ground through the back contacts of relay 161. As soon as magnet 165 completes its stroke the 40 circuit of the relay 161 is completed, thereby opening the circuit of the magnet itself and removing ground from the locking contact of relay 167. As soon as the wiper 172 engages an idle contact, when the relay 161 is 45 energized, then relay 167 will fall back preventing further action of the switch E. This relay in falling back opens the circuit of the relay 164 thereby closing the tip and sleeve conductors. 50 At the first vertical step of the switch E the cam springs 158 are opened, thereby disconnecting relays 162 and 167 from the tip and sleeve conductors. 55 At the first action of the relay 162 the circuit of the relay 163 is closed and the circuit maintained to ground over the test wire 152. The switch X^1 will continue to rotate until the starting contact is again reached and when this contact is reached the magnet 709 has its circuit completed and the switch X^2 in taking another step places relay 706 in 60 series with relay 272, Fig. 4, over the tip conductor. The action of the relay 272 closes the circuit of the stepping magnet 181 of the switch 65 F and this switch will step in unison with the switch X^1 until the wiper of this latter switch picks out the button depressed in the row 698. As soon as this button is picked out, the circuit of the stepping magnet 709 is completed and the switch X^2 takes another step thereby disconnecting relay 706 from relay 272. While relay 272 is operating however, it closes the circuit of the stepping magnet 181 by the following path: 70 ground, contacts of relay 272, 220, contacts of relay 279, 221, 181, 222, contacts of relay 276, 278 to battery B. The switch F will continue to rotate and take a number of steps corresponding to the button pressed in the 80 row 698. The action of relay 272 also closes the circuit of the relay 275. After the switch X^2 takes a step when the button pressed in the row 698 is picked out, then relay 706 is placed in series with coil 85 735 and the switch X^1 will continue to rotate. When the starting contact is again reached, the magnet 709 has its circuit closed and the switch X^2 will take another step thereby placing relay 706 in series with relay 90 270 over the sleeve side of the trunk. The action of the relay 706 will cause the switch X^1 to rotate and the action of the relay 270 will close the circuit of the rotary magnet of the switch G by the following path: ground, 95 contacts of the relay 270, 227, cam springs 295, 228, 185, to battery B. The switch G and the switch X^1 will continue to step in unison until the button pressed in the row 996 is picked out whereupon the circuit of the magnet 709 is completed causing the switch X^2 to take another step, thereby disconnecting relay 706 from relay 270. The circuit of the relay 706 will now be maintained in series with the coil 735. The circuit of the relay 270 being broken, the switch G will bring its wipers in line with a row of contacts, corresponding to the button pressed in the row 696. Relay 270 in operating, disconnects relay 275 and closes the circuit of relay 279 by the following path: ground, contacts of relay 161, Fig. 3, 156, 172, 229, contacts of relay 270, 230, 279, 222, contacts of relay 276, 278, to battery B. The operation of relay 279 disconnects magnet 100 181 and in its place connects the vertical magnet 184. 105 The switch X^1 will continue to rotate and when the starting contact is again reached, the circuit of the magnet 709 will be closed 110 and the switch X^2 will take another step and connect relay 706 again in series with relay 272 over the tip conductor. The operation of relay 272 will now close the circuit of the vertical magnet 184 causing the switch G to 115 step vertically until the circuit of the relay 272 is opened which will happen when the button pressed in the row 697 is picked out by the switch X^1 . As soon as this button is 120 picked out, magnet 709 has its circuit closed 125 130

and the switch X^2 takes another step, thereby disconnecting relay 706 from relay 272. When the wiper of the switch X^1 reaches the test contact, the circuit of the magnet 709 is closed again causing the switch X^2 to take another step, thereby placing relay 706 in series with relay 270 over the sleeve conductor. After the switch X^1 engages the test contact, it takes one step and then engages the shifting contact, thereby closing the circuit of the magnet 709, causing the switch X^2 to take another step.

The switch X^1 in stepping from the test to the shifting contact causes the relay 270 to receive one impulse. The result of this impulse is to connect the test relay 274 to the test wiper 291 by the following path: ground, contacts of relay 161, Fig. 3, 156, 172, 229, 274, 224, contacts of relay 270, 225, 20 to the test wiper 291. If the called for line is busy, there would be a difference of potential on the contact engaged by the test wiper and the relay 274 would become energized. The energizing of this relay closes the circuit of relay 285 which in turn closes the circuit of the release magnet 286 restoring the switch G to its normal position.

The action of the relay 274 connects a suitable busy tone test 215 to the calling subscriber notifying him that the called for line is busy. In case the called for line is not busy, then relay 274 is not actuated and the wipers of the switch G are allowed to come into engagement with and rest on contacts of the called line. After the relay 270 responds to the test impulse and unlocks relay 275, then relay 277 is placed in series with the cut-off relay of the called line by the following path: battery B, 277, back contacts of relay 285, 226, back contacts of relay 270, 225, 291, cut-off relay to ground. The operation of the relay 277 closes the tip and sleeve conductors, disconnects relay 272 and also closes the circuit of the relay 282 by the following path: ground, 282, 238, contacts of relay 277, contacts of relay 279, back contacts of relay 275, 220, contacts of relay 279, 223, 184 to battery B. The operation of relay 282 connects generator current of the frequency selected by the switch F to either the tip or sleeve side of the line and the coil 300 to the opposite side of the line to which the generator current is connected.

The coil 300 forms the return path for generator current which flows through the bell of the called subscriber.

While generator current is connected to the called subscriber's line through its associated commutator, relay 283 is deenergized. During the silent interval, or when generator current ceases to flow through the commutator, then relay 283 is energized by the commutator 236 connecting ground to its winding by the following path: ground, 236, winding of relay 283, 237,

contacts of relay 282, 235, coil 273 to battery B. The relation of the commutator 336 is such that it closes the circuit of relay 283 after generator current is disconnected by the ringing commutators. The action of the relay 283 connects the tip relay 276 to either the tip or sleeve conductor depending upon the wiper of the portion J. We will assume that the generator 256 is connected to the sleeve side of the line, which will be by the following path: ground, 256, its associated commutator, 251, 240, contacts of relay 282, contacts of relay 277, 202, 290, to the sleeve side of the line. The coil 300 will be connected to the tip side of the line by the following path: ground, 300, 207, H, 206, contacts of relay 282, back contacts of relay 285, 204, to the tip side of the line through the wiper 290. During the non-ringing interval or when relay 283 is energized, then relay 276 is connected to the tip side of the line by the following path: ground, 276, 208, contacts of relay 283, 209, 207, H, 206, contacts of relay 282, contacts of relay 285, 204, to the tip side of the line to wiper 290. The coil 300 is also connected to the tip side of the line and therefore the winding of the relay 276 is in multiple with it. During this period, the free side of battery is connected to the sleeve side of the line in place of the generator 256. The commutator is divided into two portions, one portion of which connects generator current, after which generator current is disconnected and replaced by battery current.

If the called subscriber should answer at this period relay 276 becomes energized thereby disconnecting relay 279. Relay 279 going back disconnects relay 282 which formerly had its circuit closed in series with magnet 184. The falling back of relay 282 disconnects generator current and also relay 283, thereby preventing its circuit being closed by the action of commutator 236. After relays 282 and 283 fall back the talking circuit is closed through from the calling to the called subscriber as indicated by the heavy lines. After relay 282 falls back, relay 276 is connected directly to the tip side of the line without having the coil 300 in multiple with its winding. Battery supply for the called subscriber is furnished through the winding of relay 276 and the retardation coil 280.

Referring to Fig. 9, it will be noted that at the first impulse sent over the tip conductor the circuit of relay 555 is closed as it is connected directly to the tip conductor through the contacts of relay 554. Relay 555 responds to the first impulse and in operating removes ground from the locking contact of relay 554. Relay 554 falling back disconnects relay 555 from the tip conductor. The circuit of relay 552, whose winding forms the locking circuit for the tens and

units relay, Fig. 8, now has its circuit maintained or controlled by relay 550 which connects ground to its winding as follows: ground, contacts of relay 550, 548, contacts 5 of relay 553, 556, to the winding of the relay 552. Relay 550 remains energized while the impulses are being transmitted. After all the impulses have been transmitted the circuit of the relay 550 is broken, thereby 10 releasing relay 552 and freeing the tens and units relays, Fig. 8. After the last test impulse has been transmitted to the connector switch the switch X^1 takes another step and when the shifting contact is reached, the circuit of the magnet 709 is again closed, which 15 causes the switch X^2 to take another step. In taking this step the circuit of the relay 653, Fig. 12, is closed by the following path: ground, 692, 667, 653, to battery B. The 20 operation of the relay 653 connects ground to the contact spring of the magnet 709 and also to the winding of the magnet 709, through the back contact of the relay 708. The circuit of the magnet being closed 25 causes it to operate its contact springs, thereby closing the circuit of the relay 708 which in operating, opens the circuit of the magnet itself. As soon as the magnet circuit is opened, its armature drops back and opens 30 the contact springs thereby removing ground from the winding of relay 708. This relay in falling back again connects ground to magnet 709. This action will continue until the wiper of the portion 692 of the switch 35 X^2 reaches its normal or starting position. As soon as this position is reached, the circuit of the relay 653 is opened thereby disconnecting ground from magnet 709.

While relay 653 is operating, ground is 40 removed from the locking contact of the relay 654 and it therefore drops back and opens the starting circuit for switch X^1 . The removal of ground by relay 653 from the locking contact of the relay 654 also 45 opens the circuit of the relays 550, Fig. 9 and 114, Fig. 2.

Relay 550 falling back removes ground from the locking contact of the relay 553, and also from the winding of the relay 552. 50 Ground being removed in this manner unlocks relays 521 and 531, Fig. 8, thereby disconnecting the secondary trunk, Fig. 9, from the primary trunk, Fig. 2. Relay 553 falling back allows the starting wires for the 55 tens and units relays to be continued so that other calls can be originated. Relay 114 falling back closes the tip and sleeve conductors so as to complete the talking circuit from the calling to the called subscriber.

60 At the operation of the relay 653, Fig. 12, ground is removed from the locking contacts of relays 601 and 611, Fig. 11, thereby disconnecting the tertiary trunk, Fig. 12, from the secondary trunk, Fig. 9. Relay 653 will 65 remain energized until the switch X^2 reaches

its normal position and while energized keeps the starting circuit for its trunk opened, but at the same time continues the starting circuit on to the next trunk in order. After switch X^2 reaches its normal position, 70 relay 653 falls back and the tertiary trunk and its associated key board are ready for other incoming calls. At the first operation of the relay 653, relay 651 falls back and would ordinarily complete the starting circuit of its trunk but this circuit however is maintained open by the action of the relay 653 but continued on to the next trunk through contacts of relay 649. 75

The calling and the called subscriber are 80 now connected through the primary set of relays, (Fig. 1,) the primary trunk, (Fig. 2) second selector, (Fig. 3) connector, (Fig. 4) and the line circuit, (Fig. 5).

At the end of the conversation, the calling subscriber hanging up his receiver, opens his line circuit, thereby deenergizing relay 111, (Fig. 2). This relay falling back removes ground from the winding of the slow relay 109. This latter relay falling back 90 closes the circuit of relay 117 by the following path: ground, contacts of relay 118, 130, wiper 142, test contacts and wiper 143, 129, contacts of relay 109, 131, 117, to battery B. The operation of relay 117 completes the 95 circuit of the release relay 115 by the following path: ground, contacts of relay 119, contacts of relay 109, contacts of relay 117, 133, 115, to battery B. Relay 115 operating has its circuit maintained to ground 100 through the cam springs 128 of the switch D. The operation of relay 117 severs the tip and sleeve conductors of the primary trunk so as to prevent interference while the switch D is restoring and its wipers passing 105 over busy contacts. The operation of relay 115 completes the circuit of the release magnet 121, thereby causing the switch D to restore to its normal position. The operation of the relay 115 also removes ground from 110 the locking wire 122 leading to the tens and units relays 1 and 11 respectively. These two relays falling back disconnect the calling line from the primary trunk. Relay 110 is thereby disconnected from cut-off relay 41. 115

When the switch D reaches its normal position, the circuit of the relay 115 is opened and in falling back, this relay again connects ground to the locking wire 122. 120

As soon as the wipers 142 and 143 leave the contact leading to the second selector switch, ground is removed therefrom, thereby unlocking relay 163, Fig. 3. This relay falling back closes the circuit of relay 164 125 by the following path: ground, cam springs 151, 154, contacts of relay 163, 155, 164, to battery B. The operation of relay 164 severs the tip and sleeve conductors and completes the circuit of release magnet 168 by 130

the following path: ground, contacts of relay 167, contacts of relay 164, 168 to battery B. The operation of magnet 168 restores the switch E to its normal position. While this switch is restoring ground is connected to the test wire 152, by cam springs 151, through the back contact of relay 163. Ground is connected in this manner so as to render the switch busy until it reaches its normal position.

When the called subscriber hangs up his receiver, his line circuit is broken, thereby causing relay 276 to fall back. This relay falling back completes the circuit of the stepping magnet 181 by the following path: battery B, 278, back contacts of relay 276, 222 and 181, 221, back contacts of relay 279, 220, back contacts of relay 275, back contacts of relay 279, portion I of the switch F, commutator 253 to ground. The magnet 181 will continue to vibrate until wiper of the portion I reaches contact 236 thereby disconnecting commutator 253. Before the contact 236 is reached, the circuit of relay 285 is closed by the following path: ground, portion H of the switch F, 232, winding of relay 285 to battery B. The operation of relay 285 severs the tip and sleeve conductors and closes the circuit of release magnet 286 by the following path: ground, contacts of relay 275, 233, contacts of relay 285, 234, 286 to battery B. The operation of magnet 286 restores the switch G to its normal position. When the wiper of the portion H reaches contact 234, the circuit of relay 285 is broken, thereby opening the circuit of the release magnet 286.

In case the called for subscriber does not answer his telephone, then the calling subscriber also controls the release of the connector switch G. In releasing the second selector switch, Fig. 3, ground is removed from the test wire 229, thereby releasing relay 279 and the circuit of magnet 181 is closed by the same path as previously traced. The action of this magnet causes the switch F to rotate and just before its normal position is reached the switch G is restored to its normal position in the same manner as previously described.

Referring now to the plan shown in Fig. 14, it will be seen from the foregoing description that the calling lines appear in the contacts of the tens relays of the primary set and the primary trunks are connected to multiple contacts in the units relays of the primary set. In this case ten tens relays and ten units relays are associated with each primary trunk so that any one of the hundred lines can become connected to the trunk.

The primary trunks appear in the contacts of tens relays of the secondary set and the secondary trunk is multiplied to the contacts in the units relays. With this arrangement, it is possible to connect any one of

the hundred primary trunks to the secondary trunk. In this case, ten tens relays and ten units relays are associated with each secondary trunk. The secondary trunks appear in the contacts of the tens relays of the tertiary set and the tertiary trunk or keyboard is multiplied to the contacts in the units relays. Each tertiary trunk has associated with it ten tens and ten units relays, thereby making it possible to connect with any one of the hundred secondary trunks.

The number of secondary and tertiary trunks provided will depend upon the size of the exchange and also upon traffic conditions, as enough keyboards would have to be furnished to take care of incoming calls without undue delay.

Referring to Fig. 16, the method of selection is shown when the various figures are used as shown in Fig. 17.

The primary and secondary selection is the same as in Fig. 14. Instead of however providing each tertiary trunk or keyboard with a set of tens and units relays, the secondary trunks themselves are each provided with a set of tens and units relays for picking out a tertiary trunk or keyboard. In fact, the secondary trunks are provided with two sets of relays, one for picking out the primary trunk and the other for picking out a keyboard.

The secondary trunk in this case is multiplied to contacts in the units relays of the secondary set and also with contacts in the units relays of the tertiary set. The keyboards or tertiary trunks are connected to the contacts in the tens relays of the tertiary sets.

I will now describe the operation of the various modifications when the figures are arranged in accordance with Fig. 17.

The calling subscriber is connected to the secondary trunk, Fig. 9^a in the same manner as previously described when the various figures are arranged in accordance with Fig. 15.

When connection is made to Fig. 9^a through the secondary set of relays, Fig. 8, then relay 852 forms part of the locking circuit for the tens and units relays, Fig. 8, as ground is connected to one terminal through the contact of relay 851. Relay 852 in operating closes the circuit of relay 854 by the following path: ground, contacts of relay 852, 848, contacts of relay 851, 841, 854, to battery B. The operation of the relay 854 connects relay 855 to the tip conductor 513. Relay 854 after being operated has its circuit locked to ground through the contacts of relay 855. The operation of relay 852 also connects ground to the starting wire leading to Fig. 10^a. Ground being placed on the starting wire closes the circuit of the relay 871 by the following path: ground, contacts of relay 852, 847, contacts of relay 130

853, 856, 871 to battery B. The operation of relay 871 closes the circuit of relay 930 by the following path: ground, contacts of relay 881, 887, contacts of relay 871, 845, 5 contacts of relay 853, 846, contacts of relay 852, 857, 930 to battery B. The operation of relay 930 connects the starting wires of the tens and units relays, Fig. 11^a, to contacts of relays 949 of the various tertiary trunks, Fig. 10 12^a. These relays 949 correspond to the line 10 relays and when operated, connect ground to the tens and units starting wires so as to operate the proper tens and proper units relays. The tens and units relays operating 15 will correspond to the number of the trunk just the same as the tens and units relays of the primary set when operated will correspond to the number of calling line. The operation of relay 930 places tens and units 20 relays associated with a secondary trunk, Fig. 9^a, in condition to be operated. The proper tens and units relays of the set are operated when the circuit of relay 949 of an idle trunk is closed by the following path: 25 ground, contacts of relay 871, 860, 868, 870, 867, contacts of relay 951, 961, contacts of relay 953, 970, 949 to battery B. The operation of relay 949 closes the circuit of the tens relay, Fig. 11^a, by the following path: 30 ground, contacts of relay 953, 962, contacts of relay 951, 961, contacts of relay 949, 939, contacts of relay 930, 937, tens relay 911 to battery B. The units relay is closed by the following path: ground, contacts of relay 35 953, 962, contacts of relay 951, 961, contacts of relay 949, 938, contacts of relay 930, 936, units relay 901 to battery B. The operation of the tens and units relays connects the primary trunk to the tertiary trunk, Fig. 12^a, 40 thereby placing relays 950, 850 and 114 in series by the following path: ground, contacts of relay 953, contacts of relay 954, 963, contacts of relay 952, 975, 950, 934, contacts of relay 911, 924, contacts of relay 901, 814, 45 850, 518, contacts of relay 531, 508, contacts of relay 521, 108, contacts of relay 115, 109, 114 to battery B. The operation of relay 950 closes the circuit of relay 951 and the operation of this relay removes ground from 50 the tens and units starting wires leading to relays 901 and 911. These two relays however have their locking circuits maintained to ground through the winding of relay 852, Fig. 9^a. The operation of relay 951 disconnects the starting wire 867 from its associated trunk and continues it to the next trunk in order through the back contacts of relay 949. 55 The operation of relay 850 completes the 60 circuit of relay 853 which in operating releases relay 871 and relay 930. Relay 853 remains energized while the secondary trunk is in use and prevents any further operation of any relay of the set, Fig. 11^a, by other 65 calls. In order to operate any relay of the set, it is necessary for relay 930 to be energized. The operation of the relay 850 closes the circuit of the relay 851. The operation of this latter relay disconnects ground from the winding of the relay 852 but the circuit 70 of this relay is maintained to ground through the contacts of relay 850.

The operation of relay 950 causes the two lamps 700 and 701 to light, notifying the operator of the call. 75

The various switches are controlled in the same manner as described in connection with Fig. 15 and need not be described again. At the first impulse sent over the tip side of the trunk relay 855, Fig. 9^a, responds and disconnects relay 854 and this relay falling back removes relay 855 from the tip conductor. 80

After all the impulses have been transmitted, relay 953, Fig. 12^a is energized causing the switch X² to restore to its normal position and also opens the circuits of the relays 954, 850 and 114. Relay 850 falling back removes ground from the winding of the relay 852. The removing of ground in 90 this manner releases the tens and units relays 911 and 901, Fig. 11^a, and the tens and units relays 521 and 531, Fig. 8. The falling back of these relays disconnects the secondary trunk from the primary trunk and the 95 secondary trunk from the tertiary trunk. 100

The control circuit shown in Fig. 10^a can be made common to a certain group of secondary trunks, Fig. 9^a; for instance, if the secondary trunks are in groups of one hundred, then relay 871 would be common to ten trunks, relay 872 common to ten trunks and relay 873 common to ten trunks. To each group of ten trunks, there would be one of these control relays and it naturally follows that to one hundred trunks, ten of these relays would be provided. The control circuit is so arranged that only one relay 930 of a hundred secondary trunks can become energized at one time. The hundred secondary trunks can be divided into sub-groups of ten trunks each. The control circuit, Fig. 7, can be common to 100 primary trunks such as shown in Fig. 2. It therefore follows that any one of the one hundred primary trunks serving one thousand lines can become connected to any one of the ten secondary trunks allotted to its group. I have previously explained in connection with Figs. 1 and 6 how a set of tens and units relays and their associated controlling relays are common to a group of 100 lines. The primary trunks, one of which is shown in Fig. 2, can be arranged in like manner whereby the control relays and circuit arrangements of Fig. 7 can be common to a group of 100 primary trunks. 110

The calls from one group of primary trunks will become connected to the secondary trunks of its group one at a time by 115 120 125 130

means of the control relays and circuit arrangements of Fig. 7. The switch N in Fig. 7 selects an idle secondary trunk of its group in the same manner previously explained, and after the proper relays are operated as described this switch then steps and selects another idle secondary trunk in case there is another call.

The operation of the various relays for effecting the connections is practically instantaneous and selection is effected by the time the switch N is in condition to select another idle trunk. The controlling relay 471 which is made sluggish in its action is timed to allow sufficient time intervals between selections for the various relays to perform their functions. This arrangement allows one call from each group of the one hundred primary trunks to become connected to the secondary trunk at a time. According to this arrangement only one relay 852 will be energized and one relay 853 deenergized at the same instant in a particular group of ten secondary trunks.

Simultaneous calls can occur however, one in each group of ten secondary trunks or each group of one hundred primary trunks. In case of such simultaneous calls occurring, confusion is prevented by the control circuit, Fig. 10^a. Although all ten relays 871, 872, 873, etc., become energized, only the action of one becomes effective as the control contacts which operate relay 930 are in a series relation. This series relation of the contacts prevents more than one relay 930 becoming energized at the same time. As fast however as a secondary trunk becomes connected to a tertiary trunk the next trunk in order is connected. Various methods of grouping the primary, secondary and tertiary trunks can be used. The foregoing method simply being used for illustration.

The switch U shown in Fig. 10^a is only an emergency switch and serves to guard the set of series control contacts and the set of relays 871, 872, 873, etc. In case any relay of this set is held energized for an abnormal length of time before the operation of relay 870, then the switch becomes effective. Relay 870 is placed in series with relay 949 over the starting wire and should act as a tertiary trunk or keyboard is picked out. In case of failure to act the following function will be performed by the switch U: Relay 893 operates when any one of the relays 871, 872, 873, etc., is operated and connects a commutator 890 to the stepping magnet 882 of the switch U, thereby causing this switch to step in the direction indicated by the arrow. When the wiper of the portion u reaches a contact to which relay 880 is connected, then the circuit of this relay is completed by the following path: ground, contacts of relay 870, 892, contacts of relay 893,

888, u, 883, 880 to battery B. The operation 65 of relay 880 connects winding of relay 881 to another set of contacts of the portion u. The switch U after taking a certain number of steps, reaches one of the last mentioned contacts, thereby closing the circuit 70 of relay 881 by the following path: ground, contacts of relay 870, 892, contacts of relay 893, 888, u, 884, contacts of relay 880, 889, 881, to battery B. Relay 881 becoming energized is locked to ground through the contacts of relay 893 and relay 870. Relay 880 is also locked to ground in the same manner. The operation of relay 881 removes ground from the series contact of the relay 871 and connects ground to portion u¹ of the switch 80 U. This switch will continue to step and the wiper of the portion u¹ passing over contacts, connects ground to each control contact of the set of the control relays. In case relay 872 were energized and there should 85 be a bad contact in relay 871 or 881, then the action of relay 872 could not connect ground to its control wire 866. In such an event however the switch U would be brought into action and when the wiper of 90 the portion u¹ reaches the contact to which wire 869 is connected then the action of relay 872 would become effective and ground would be placed on wire 866 regardless of the condition of the control contacts of relays 871 or 881. As soon as relay 872 becomes effective then relay 870 is at once energized, being in series with the common starting wire. The action of the relay 870 removes ground from the locking contacts 95 of relays 880 and 881 thereby preventing the switch U causing any effect on the control contacts of relays 871, 872, 873, etc.

The emergency switch K, Fig. 6, acts in the following manner in case of faulty connection: In case the test relay 352 of the switch L remains energized for an abnormal length of time after an idle primary trunk has been selected then the switch K becomes effective. Relay 353 is energized by any one 105 of the relays 321, 322, 323, etc., and connects the interrupter and commutator 320 to the stepping magnet 355 of the switch K by the following path: ground, 319, contacts of relay 353, 315, contacts of relay 352, 316, 355 110 to battery B. The switch K will step once at each closure of the commutator 320, and when the portion 359 of the switch K reaches an active contact the circuit of the relay 356 is closed by the following path: battery B, 356, 303, 359, 313 to ground through the contacts of relay 352. Relay 356 operating, locks itself to ground through the contacts of relay 352 and also connects ground to the portion 358 of the switch K. When the 115 wiper of this portion reaches an active contact the circuit of relay 357 is closed. The action of this relay connects ground to relay 120

63, Fig. 1, by the following path: ground, contacts of relay 357, contacts of relay 352, 65 317 to portion 360 of the switch L, 60, 63, to battery B. The operation of relay 63 re-
5 moves ground from the locking contacts of any tens or any units relays energized, thereby restoring them to their normal position. The action of relay 357 also connects ground to the stepping magnet 363 of the switch L
10 through contacts of relay 354, thereby causing the wiper of the switch L to take another step and leave the contacts formerly engaged by its wipers. The switch L in taking this step causes relay 352 to fall back,
15 thereby releasing relay 356 and preventing further action by the switch K.

Having thus described my invention, what I desire to secure by Letters Patent is:

1. In a telephone exchange system, the 20 combination with a plurality of groups of primary trunks, of a single group of key sets, a plurality of intermediate trunks, said key sets being associated with a plurality of groups of intermediate trunks, each 25 group of intermediate trunks being associated with a plurality of groups of primary trunks, and selective means comprising sets of tens and units relays whereby any one of the group of intermediate trunks can be 30 selectively connected to any primary trunk in a plurality of groups of primary trunks, and additional selective means comprising sets of tens and units relays whereby said single group of key sets can be selectively 35 connected to a plurality of groups of intermediate trunks, substantially as set forth.

2. In a telephone exchange system, the combination with a group of primary trunks, of a group of key-sets, intermediate trunks 40 interposed between said primary trunks and key-sets, and selective means comprising a set of tens and units relays, whereby a primary trunk is extended to an intermediate trunk, and additional selective means comprising a set of tens and units relays whereby said intermediate trunk is extended to a key-set of the group, substantially as set forth.

3. In a telephone exchange system, the 50 combination with a plurality of calling subscribers' lines, of a plurality of key-sets, and means comprising primary, secondary and tertiary selecting devices whereby any calling subscriber's line is connected to the first 55 idle one of said key-sets, said primary, secondary and tertiary selecting devices comprising groups of tens and units relays, substantially as set forth.

4. In a telephone exchange system, the 60 combination with a selector switch, of an operator's key-board, an auxiliary switch associated with said key-board, a control circuit extending between the key-board and selector switch, and means controlled at the

auxiliary switch for interrupting said control circuit to cause the operation of said selector and auxiliary switch in unison, means for continuing said interrupting means until said auxiliary switch selects the depressed button on said key-board, substantially as set forth.

5. In a telephone exchange system, the combination with a selector switch, interrupting means for said selector switch comprising a stepping magnet, a relay for operating said magnet, of an operator's key-board comprising two automatically operated switches, a control circuit extending between said key-board and said selector switch, and means exercised over said control circuit whereby the interrupting means in said selector switch is disabled when said switches coöperate to pick out the depressed key on the key-board, substantially as set forth.

6. In a telephone exchange system, the combination with an operator's key-board consisting of a plurality of rows of keys, a single auxiliary step-by-step switch associated with said key-board adapted to be 90 stepped from a normal position over stationary contacts individual to keys in such rows of keys for selecting the depressed buttons in said rows of keys, a second step-by-step switch associated with said key-board for 95 rendering the depressed button selectable by the first said auxiliary switch, substantially as set forth.

7. In a telephone exchange system, the combination with an impulse controlling device, a single automatically operated step-by-step switch associated with said controlling device for determining the number of impulses to be transmitted, a second step-by-step automatically operated switch associated with said controlling device for regulating the order in which said impulses are to be transmitted and means operated in the movement of such first-mentioned switch to generate the impulses transmitted, substantially as set forth.

8. In a telephone exchange system, a selector switch, a control circuit and an impulse transmitter for impressing impulses on such control circuit, said impulse transmitter 115 comprising a key-board having a plurality of rows of keys, two step-by-step switches, stepping magnets therefor, one of said switches regulating the number of impulses, the other one of said switches determining 120 the order in which the impulses are controlled, and means operative by the stepping magnet of the first of such switches for impressing impulses on such control circuit.

9. In a telephone exchange system, the 125 combination with a selector switch, of an impulse transmitting device, means associated with said device for initially causing

the actuation of said selector switch at the transmission of each impulse, means associated with said selector switch after transmission of each impulse to in turn control 5 the action of said impulse transmitting device, substantially as set forth.

10. In a telephone exchange system, the combination with an automatic switch and actuating means therefor, of an impulse 10 transmitting device, means associated with said device for causing the initial operation of the actuating means of said automatic switch at the transmission of each impulse, means associated with the actuating means 15 after the transmission of each impulse for in turn controlling said transmitting device, substantially as set forth.

11. In a telephone exchange system, the combination with an automatic switch, actuating means for said switch comprising a magnet and a relay for operating said magnet, of an impulse controlling device, actuating means for said controlling device comprising a magnet and a relay, the winding 25 of which is of a high resistance as compared with the winding of the relay associated with said automatic switch, means whereby when the two relays are placed in series the actuating means for said controlling device 30 is operated, after which the actuating means for said automatic switch is operated by the actuating means of said controlling device, said actuating means for the automatic switch in turn regulating the actuating means for said controlling device, substantially as set forth.

12. In a telephone exchange system, the combination with a group of primary trunks, of a group of key-sets, intermediate 40 trunks interposed between said primary trunks and key-sets, a selective means comprising a set of tens and units relays whereby a primary trunk is extended to an intermediate trunk, and additional selective 45 means comprising a set of tens and units relays whereby said intermediate trunk is extended to a key-set of the group, substantially as set forth.

13. In a telephone exchange system, the combination with a plurality of calling subscribers' lines, of a plurality of key-sets and means comprising primary, secondary and tertiary selections whereby any calling subscriber's line is connected to the first idle 55 one of said key-sets, said primary, secondary and tertiary selections being accomplished by means of groups of tens and units relays, substantially as set forth.

14. In a telephone exchange system, the combination with an automatic switch, a

stepping magnet for said switch and a primary relay for operating said magnet, an impulse device comprising an auxiliary switch, a magnet for operating said auxiliary switch and a secondary relay for operating 65 said magnet, means whereby when both of said relays are placed in series the secondary relay is actuated to operate the stepping magnet of the auxiliary switch, means controlled by said magnet when so 70 operated for disabling said secondary relay and thereby causing the operation of the primary relay to operate the magnet of the automatic switch, and means controlled by said magnet when operated for disabling 75 both of said relays, substantially as set forth.

15. In a telephone exchange system, the combination with an automatic switch, a stepping magnet for said switch and a primary relay for operating said magnet, a resistance coil in series with the winding of said relay, an impulse device comprising an auxiliary switch, a magnet for operating said switch and a secondary relay for operating 80 said magnet, means whereby when both of said relays are placed in series the secondary relay is actuated to operate the stepping magnet of said auxiliary switch, means controlled by said magnet when so 85 operated for short circuiting said secondary relay and causing the operation of the primary relay to operate the magnet of the automatic switch, and means controlled by said magnet when operated for disabling both of said relays, the disabling of both of 90 said relays being accomplished by changing the potential between the winding of the primary relay and said resistance coil, substantially as set forth.

16. In a telephone exchange system, the combination with an automatic switch, actuating means for said switch, a relay for operating said actuating means, a controlling device having an associated secondary relay, actuating means for said device, means 105 for placing both of said relays in series whereby the secondary relay is operated to render active the actuating means for disabling the secondary relay and for causing the operation of the primary relay, and 110 means controlled by the actuating means of the automatic switch when operated to disable both of said relays, substantially as set forth.

In testimony whereof I affix my signature 115 in presence of two witnesses.
